UNITED STATES PATENT OFFICE.

HENRY B. ZIMMERMAN, OF RAYMOND, MINNESOTA.

HAY-RICKER.

No. 830,035.

Specification of Letters Patent.

Patented Sept. 4, 1906.

Application filed March 13, 1906. Serial No. 305,910.

To all whom it may concern:

Be it known that I, HENRY B. ZIMMERMAN, a citizen of the United States, residing at Raymond, in the county of Kandiyohi and 5 State of Minnesota, have invented a new and useful Hay-Ricker, of which the following is a specification.

This invention relates to hay rickers or loaders, and its object is to provide a device 10 of this character having a fork of novel construction to raise hay or other material to a desired point, whereupon the same will be discharged automatically, thus permitting the operator to properly build the hay-stack.

With the above and other objects in view 15 the invention consists of a base having side beams pivoted thereto and provided at their upper ends with a stationary fork-section. Another fork-section is pivoted to the first- 20 mentioned section and is normally supported at right angles thereto by resilient means provided for that purpose. An actuating-beam is pivotally mounted upon the base and connected to the forks so as to swing the 25 side beams to a desired angle in relation to the base. This beam is adapted to be actuated by any suitable power. Adjustable means are also employed for causing the swinging fork-section to automatically dis- 30 charge the load after the fork reaches a predetermined position.

The invention also consists of certain other 35 novel features of construction and combination of parts, which will be hereinafter more fully described, and pointed out in the claims.

In the accompanying drawings is shown 40 the preferred form of the invention.

In the said drawings, Figure 1 is a perspective view of the device in position to receive 45 material prior to discharging it upon a stack, and Fig. 2 is a side elevation showing the position assumed when the load is being discharged.

Referring to the figures by numerals of reference, 1 1 are the sides of the base of the loader, and 2 and 3 are the end beams which are secured thereon, said side beams being preferably beveled at their ends, so as to facilitate dragging the loader from place to 50 place. A cross-rod 4 is secured upon the side beams 1 near the forward end thereof and constitutes the pivot of the fork-frame. This frame is formed with upstanding beams 5, connected at their upper ends by cross-strips 55 6, and secured on these cross-strips are the

fingers 7, constituting the stationary section of the fork. A series of connected fingers 8 is pivoted to the lower ends of fingers 7, and rods 9 are pivotally connected to the fingers 8 and slide within guides 10, extending laterally from the beams 5. Coiled springs 11 are disposed upon the rods 9 and bear at opposite ends on the guides 10 and the movable fork-section 8, respectively. These springs serve to normally hold the movable fork-section 60 substantially at right angles to the fingers 7. Holdback ropes or cables 12 extend from the lower ends of the rods 9 and are adjustably fastened in any desired manner to a beam 13, which is pivotally mounted on the 65 rear end beam 3 and is adapted to hold the ropes 12 normally taut.

An actuating-lever 14 is disposed upon the base and projects through the fork-frame 5. This lever consists of converging pairs of up- 70 rights 15, said pairs being spaced apart at their upper ends by a connecting-strip 16, so as to give the actuating-lever a triangular appearance. The connecting-strip 16 thereof is attached to the side beams 5 by means of 75 rods 17, and a pulley 18 is secured to the lower end of this connecting-strip 16 and also to the center of the front end strip 2. A cable 19 is secured to said end strip 2 and extends around the pulleys. Its free end is adapted 80 to be attached to any suitable power. In using the apparatus herein described the fork is swung downward into position adjacent the rear end beam 3 and a quantity of 85 hay or other material to be stacked is placed 90 upon the fork between the two sections thereof. Horses can then be connected to the cable at 19 and when driven forward will swing the lever 14 downward. An upward pull will therefore be exerted upon the fork 95 and its frame by the rods 17 and the fork-sections will be carried to a predetermined elevation, whereupon the ropes 12 will become taut and pull downward on the rods 9. This will result in the pivoted fork-sections 100 swinging downward so as to discharge the material therefrom. The downward movement of the fork-section 8 will of course tension the springs 11. As soon as the load has been discharged in this manner the parts can 105 be returned to their original position by pressing backward on the fork-frame until the parts have passed the center of gravity. Of course as soon as the ropes 12 become slack the springs 11 return the movable fork- 110

section to its original position. By lengthening or shortening the ropes 12 the fork can be caused to discharge its load at predetermined points during its upward movement.

5 5 If desired, chains may be connected to the ends of the rods 9 and may be adjustably connected to hooks upon the side beams 5, so as to limit or prevent movement of the rods, as may be deemed necessary.

10 10 By means of mechanism such as herein described a load of hay can be stacked at any desired point and the material carried by the fork can be accurately discharged at predetermined points, so as to permit the operator 15 to properly build the stack. The pivoted beam 13 serves to keep the ropes 12 normally taut, so as to prevent them from becoming entangled in any parts of the mechanism.

15 20 I claim—

1. A device of the character described comprising a base, a fork-frame pivotally supported upon the base, a stationary fork-section secured on the frame, a pivoted fork-section upon the frame, a resilient support for said pivoted section, means for swinging the frame upon the base, and means for automatically swinging the pivoted fork-section to unload at predetermined points.

25 30 2. The combination with a base; of a fork-frame pivotally supported thereon, means for swinging the frame upward from the base, a fork-section rigidly connected to the frame, a fork-section pivotally connected to the frame, a resilient support for said pivoted section and adjustable means for automatically swinging the pivoted fork-section at predetermined points during the upward movement of the frame.

35 40 3. The combination with a base; of a fork-frame pivotally connected to the frame, a resilient support therefor and adjustable means for contracting the support at predetermined points during the movement of the

frame to swing the fork-section into unloading position.

4. The combination with a base; of a fork-frame pivoted thereon, means for swinging 50 said frame upward from the base, a fork-section pivoted upon the frame, guide-rods depending therefrom, resilient fork-supports mounted on the rods, and an adjustable hold-back device connected to the rods. 55

5. The combination with a base; of a fork-frame pivoted thereon, means for swinging the frame upward from the base, a pivoted fork-section mounted on the frame, a resilient support for said section and a holdback 60 device adjustably connected to the base for actuating the pivoted fork-section at predetermined points during the upward movement of the frame.

6. The combination with a base; of a fork-frame pivoted thereon, means for swinging the frame upward from the base, a fork-section pivoted upon the frame, guide-rods depending therefrom, resilient fork-supports upon the rods, a holdback for tensioning the 70 supports and actuating the fork-section at a predetermined point during the upward movement of the frame. 65

7. The combination with a base; of a fork-frame pivoted thereon, means for swinging 75 the frame upward from the base, a fork-section pivoted upon the frame, guide-rods depending therefrom, resilient fork-supports upon the rods, a flexible holdback connected to the rods and adapted to tension the spring 80 and actuate the fork-section at a predetermined point during the upward movement of the frame, and means for maintaining said holdback taut.

In testimony that I claim the foregoing as 85 my own I have hereto affixed my signature in the presence of two witnesses.

HENRY B. ZIMMERMAN.
